UNITED STATES PATENT OFFICE.

FERDINANDO CERBO, OF PROVIDENCE, RHODE ISLAND.

URETHROSCOPE.

1,044,348.

Specification of Letters Patent. Patented Nov. 12, 1912.

Application filed June 20, 1912. Serial No. 706,682.

To all whom it may concern:

Be it known that I, FERDINANDO CERBO, a subject of Italy, residing at Providence, in the county of Providence and State of Rhode Island, have invented a new and useful Improvement in Urethrosopes, of which the following is a specification.

My invention has reference to an improvement in urethrosopes and more particularly to an improvement in the urethroscope patented to me September 12, 1911, No. 1,003,232.

The improved instrument forming the subject of this application relates more particularly to urethrosopes or analogous tubular instruments adapted to be inserted into the urethra or other channels, said instrument being provided at its lower or distal end with means for temporarily dilating the urethral or other passage, and as employed by physicians for the purpose of making visual examinations as well as treating the urethral channel or its cavities, and to facilitate the use of other instruments in the urethral passage or other channels.

There are still disadvantages or objections to instruments or urethrosopes of the character above referred to; that is to say, they support a front cover to close the outer end of the central tube's passage in the act of irrigating and a flat flange with a gutter to collect the waste liquid flowing back between the outer tube and wall of the passage during the irrigation, the result being to have only closed the bore of the central tube without controlling the act of irrigating, as the waste liquid has free egress between the outer tube and passage and out through the gutter. The benefit of controlling the act of irrigating as well as other operations, is lost and the discomfort of the patient, by forcing the liquid to flow among the inter-spaces of the dilating elements of the instrument against the walls of the channel is increased, the act of dilating at the distal end of the dilators causing the retraction of tissues back of the cone-shaped cavity, tightening upon the tube proper and preventing the reflowing of the liquid. The tube containing the electric wire in the inner tube obstructs the free use of the auxiliary telescope and other instruments and is insanitary. The electric lamp bulb being naked is very objectionable

on account of its liability of being very easily broken in the use of instruments through the urethroscope or through other accidents. The switch and its guide located upon the concave inner side of a dilator arm and above the lamp bulb constitutes also a cumbersome arrangement; the end of the irrigating tube or nozzle which enters an opening in the side of the thin inner tube serving also to prevent the turning of the inner tube on its axis, is objectionable as the end of the telescope is liable to catch on the inner end of the tube and prevent the insertion of the telescope and finally the location of the short arms on the dilator arms forms a clogged area at their sides which is objectionable on account of examinations and other operations.

The object of my invention is to improve the construction of the said urethroscope whereby a more simple and comparatively less expensive self-contained instrument or urethroscope is produced and in which the disadvantages or objections above referred to are wholly eliminated.

My invention consists in the peculiar and novel construction of a urethroscope, said urethroscope having details of construction as will be more fully set forth hereinafter and claimed.

Figure 1. represents a side view of my improved urethroscope, somewhat enlarged, showing the dilators in their normal or closed position. Fig. 2. is a still further enlarged longitudinal sectional view, taken on line 2. 2. of Fig. 1. with the central portion broken away. Fig. 3. is an enlarged transverse sectional view taken on line 3. 3. of Fig. 1. Fig. 4. is an enlarged detail side view of a portion of the head end partly in section and showing the means for preventing the inner tube from turning on its axis. Fig. 5. is partial, longitudinal, central sectional view, still further enlarged, showing the dilator arms normally closed in full lines and in the expanded position in broken lines. Fig. 6. is a detail cross sectional view taken on line 6. 6. of Fig. 5. Fig. 7. is a detail cross sectional view taken on line 7. 7. of Fig. 5. and Fig. 8. is a sectional view of the cap for closing the open end of the outlet pipe.

In the drawings Fig. 1. represents my improved urethroscope as a whole, the same consisting essentially of the relatively sta.

tionary outer tube 9., the non-revoluble but longitudinally movable inner tube 10., a plurality of swinging, laterally movable dilator arms 11. jointed to the inner end of the outer tube; an operating member 12., a removable telescope member 13. on the head end and an electric light bulb 14. on one of the dilator arms. All of the above named elements, so far as possible may be made of 10 German silver or other suitable material.

The diameter and length of the outer tube 9. may be of any suitable dimensions, such for example as will permit the instrument to be readily inserted into the urethral passage. The end portion of the outer tube which may be termed the outer or head end is provided with a slightly enlarged cylindrical head 15. having internal screw-threads 16., a short internal longitudinal groove 17., 15 a right angle tubular boss 18. having an inlet duct 19. and a right angle tubular boss 20. for the electric light wire. A groove 21. extends longitudinally on the inside of the outer tube 9. from the boss 20. to the inner 20 end of the tube, for the electric light wire. In the outer tube 9. adjacent its inner end is formed a plurality of small rectangular shaped openings 22. 22., the end of the tube at the openings forming a hinge pivot 23., 25 one for each of the dilator arms 11. 11.

The inner tube 10. has an externally screw-threaded head end 24., a bearing ring 25., a 30 spline 26. which enters the groove 17. in the head and while allowing longitudinal movement of the inner tube prevents the inner tube from turning on its axis; and elongated inlet opening 27. in the side under the inlet duct 19., a series of depressions 28. 28., and a series of small rectangular shaped openings 29. 29. on a central longitudinal line 35 with the openings 22. 22. in the outer tube 9. one for each of the dilator arms 11. 11.

To the inner end of the outer tube 9. are hinged four circumferentially spaced elongated tapering dilator arms 11. 11. which when closed form a cone-shape inner end on the instrument, as shown in Fig. 1.; each dilator 11. being concavo convex in cross section. The free or apex end of each dilator 40 is slightly enlarged, the shape being such that when the said apex ends are in actual engagement with each other a narrow, longitudinal space is formed between the adjacent edges of each pair of dilator arms. A hook shaped tongue 30. and an inwardly extending finger 31. are formed on the tube end of each dilator arm in a position for the hook shaped tongue 30. to curve under and partly around the hinge pivot 23. and enter 45 the opening 22. in the outer tube 9., thereby hinging the dilator to the tube and for the finger 31. to enter an opening 29. 29. in the inner tube 10. thereby operatively connecting the dilator arms with the inner tube, as 50 shown in Figs. 2. and 5.

The operating member 12. is in the form of an externally screw-threaded sleeve in screw-thread engagement with the internal screw-threads 16. in the head 15. and having a knurled flange 32. The operating member 12. is rotatably secured to the head end 55 of the inner tube 10. by the bearing ring 25. and a screw-threaded collar 33. as shown in Fig. 2.

The telescope member 13. is in the form of a tube 34. having a sliding fit in the bore of the inner tube 10., a slightly enlarged head portion 35. adapted to screw over the screw-threaded end 24. of the inner tube 10. a still further enlarged end portion 36. carrying a magnifying lens 37., an outlet pipe 38. leading at right angles from the tube 34. said pipe 38. having an externally screw-threaded end 39. as shown in Fig. 2. An internally screw-threaded cap 40. as 60 shown in Fig. 8. is adapted to screw over the end of and close the open end of the outlet pipe 38. which may be of any length desired. A rubber inlet tube 41. leading from a source of fluid supply, not shown, is secured to the inlet pipe 18. and a rubber outlet tube 42. when used, is secured to the outlet pipe 38. and extends downward to a receiving receptacle, not shown.

The electric light bulb 14. is entirely and 65 permanently inclosed in a metal casing 43. having an opening or window 44. through which the light shines and a locking projection 45. One of the light terminals is attached to the metal casing 43. and the other 70 terminal at the contact point 46. A lamp clip 47. having a longitudinal slot 48. is secured longitudinally to the inside of one of the dilator arms 11. and the lamp is detachably secured to the dilator arm by inserting 75 or pushing the lamp through the clip 47. and then turning the lamp so as to bring the projection 45. against the inner end of the clip, as shown in Figs. 2. and 5. A tube 49. is secured to or may be embedded in the inner face of the dilator arm 11. An insulated 80 wire 50. is secured in the tube 49., one end 51. of the bare wire being bent into contact with the contact point 46. on the electric light bulb 14. and the other end of the bare wire 85 terminating in the end 52. at the hinge joint of the dilator arm. An insulated wire 53. extends inward from a battery, not shown, through the boss 20. and the longitudinal groove 21. and terminates in the bare end 54. 90 The bare ends 52. and 54. form contact points which come into contact and close the circuit when the dilator arms are opened. A wire 55. extends from the battery, not 95 shown, to a binding post 56. on the head 15. the metal from the binding post 56. to the clip 47. forming one half of the electric light circuit.

By means of this improved construction 100 the unobstructed insertion of a telescope or 105

instrument is readily permitted. The urethroscope when inserted, as in use, may be easily and quickly manipulated so as to accurately and positively operate the dilator arms simultaneously to the desired extent, thereby correspondingly enlarging that portion of the urethral passage and temporarily producing a complete dilation of the folds of the cavity, preparatory to examinations, forceps operation, irrigation or other operations.

In the use of my improved urethroscope the instrument first sterilized is inserted into the urethral passage or other channels to the desired extent followed by turning the operating member 12. to the right thereby correspondingly moving the inner tube 10. rightwise inward when the edges of the rings 29. 29. of the inner tube engaging with the fingers 31. 31. on the dilator arms 11. 11. thereby opening the dilator arms, bringing the ends 52. and 54. of the wires 50. and 53. into contact, closing the circuit and energizing or lighting the lamp 14. A further turning of the operating member to the right still further opens the dilator arms 11. 11. The physician may then make a visual examination or inspection of the thus acted upon parts.

When irrigating, the remedial liquid flows through the tube 41. the inlet duct 19. the opening 27. through the bore of the inner tube 10. to the enlarged portion of the urethra, then flowing back through the bore 35 of the inner tube, as in the case of a retrojector and escaping out through the outlet pipe 38. The remedial liquid is thus kept entirely out of contact with the external portions of the human body. At the completion of the operations the act of turning the operating member 12. to the left retracts the inner tube 10. and the dilator arms 11. 11. back to their normal positions and simultaneously breaking the contact of the 45 wire ends 52. and 54. opening the circuit and cutting out the electric lamp 14. The instrument is then removed from the urethra or other channel. The telescope member 13. may be easily removed by unscrewing the 50 same from the end of the inner tube 10. for the insertion of other instruments into the urethroscope.

Having thus described my invention I claim as new and desire to secure by Letters 55 Patent:—

1. In a urethroscope, an outer tube having a plurality of small rectangular openings at its inner end, the portion between the openings at the end forming hinge pivots, an 60 inner tube having a plurality of small rectangular openings at its inner end on a longitudinal line with the openings in the outer tube, and a plurality of corresponding depressions, a plurality of dilator arms, one 65 for each opening in the outer tube, said

dilator arms each having a semi-circular tongue extending under and partly around a hinge pivot and into an opening in the outer tube and an inwardly extending finger extending through an opening in the inner tube, means for holding the inner tube from turning on its axis and means for reciprocating the inner tube. 70

2. In a urethroscope, an outer tube, an inner tube, a plurality of dilator arms 75 hinged to the outer tube and operatively connected to the inner tube, an enlarged head end on the outer tube, having an internal longitudinal groove, a spline on the inner tube in operative engagement with the groove in the head, whereby the inner tube is held from turning on its axis and the dilator arms are held in their operative positions, an inlet duct in the head, an inlet slot 80 in the inner tube registering with the inlet duct in the head, an outlet duct from the inner tube and means for reciprocating the inner tube. 85

3. In a urethroscope, an outer tube, an inner tube externally screw-threaded at its 90 outer end, a plurality of dilator arms hinged to the outer tube and operatively connected to the inner tube, an enlarged head end on the outer tube internally screw-threaded and having an internal longitudinal groove, a 95 spline on the inner tube in operative engagement with the groove in the head, whereby the inner tube is held from turning on its axis and the dilator arms are held in their operative positions, a bearing ring on the 100 inner tube, a screw-threaded collar on the inner tube, an operating member rotatably secured to the inner tube by the ring and collar, said operating member having an externally screw-threaded portion in screw-thread engagement with the internal screw- 105 threads in the head and a knurled flange.

4. In a urethroscope, an outer tube having an enlarged head end internally screw-threaded and in which is a longitudinal 110 groove, an inner tube externally screw-threaded at its outer end, a plurality of dilator arms hinged to the outer tube and operatively connected with the inner tube, a bearing ring on the inner tube, a spline on 115 the inner tube, in operative engagement with the groove in the head, whereby the inner tube is held from turning on its axis and the dilator arms are held in their operative positions, a screw-threaded collar on 120 the screw-threaded end of the inner tube, an operating member rotatably secured to the inner tube by the ring and collar, and having an externally screw-threaded portion in screw-thread engagement with the internal 125 screw-threads in the head, and a knurled flange, a telescope member comprising a tube having a sliding fit in the inner tube of the urethroscope, an internal screw-threaded portion adapted to screw over the screw- 130

threaded end of the inner tube, an outlet pipe at right angles to the tube, a cap adapted to screw over the end of the outlet pipe and a lens secured to the outer or head end 5 of the member.

5. In a urethroscope having an outer tube, inner tube, dilator arms hinged to the outer tube and operatively connected to the inner tube, an electric lighting system comprising 10 an electric lamp, permanent metal casing inclosing the lamp and having a light opening, said lamp having one pole connected to its casing and the other pole connected to a contact point at the end of the lamp, means 15 for detachably and electrically securing the lamp to one of the dilator arms, an electric circuit comprising a wire electrically connected to the instrument and an insulated wire extending between the tubes through a 20 longitudinal groove in the outer tube and terminating at the inner end of the outer tube, a suitably mounted insulated wire extending from the contact point of the lamp to the hinged end of the dilator arm, the 25 ends of the wires being so placed that on the opening of the dilator arm the ends of the

wires come into contact, thus closing the circuit and electrically energizing the lamp.

6. In a urethroscope, an outer tube having an inner longitudinal groove for an electric light wire, an inner tube having a sliding fit in the outer tube, a plurality of dilator arms hinged to the outer tube and operatively connected to the inner tube, an enlarged head end on the outer tube having a 30 short internal longitudinal groove, a spline on the inner tube in operative engagement with the groove in the head, whereby the inner tube is held from turning on its axis and the dilator arms are held in their operative positions, an inlet duct in the head, an inlet slot in the inner tube registering with the inlet duct in the head, an outlet duct from the inner tube and means for reciprocating the inner tube. 35

In testimony whereof, I have signed my name to this specification in the presence of two subscribing witnesses.

FERDINANDO CERBO.
